UNITED STATES PATENT OFFICE.

FRED A. REARDON, OF BRIDGEPORT, CONNECTICUT, ASSIGNOR TO HAMEL SHOE MACHINERY COMPANY, OF BRIDGEPORT, CONNECTICUT, A CORPORATION OF MASSACHUSETTS.

HEEL-NAILING MACHINE.

Application filed December 8, 1920. Serial No. 429,095.

To all whom it may concern:

Be it known that I, FRED A. REARDON, a citizen of the United States, residing at Bridgeport, in the county of Fairfield and 5 State of Connecticut, have invented certain new and useful Improvements in Heel-Nailing Machines, of which the following is a specification, reference being had therein to the accompanying drawings.

10 This invention relates to machines for use in nailing heels on footwear and is more particularly designed for use where the nails are driven from within the shoe.

One feature of this invention relates to 15 means whereby the spacing of the nails and the direction in which they are driven may be adjusted to suit varying sizes and shapes of heels.

A further feature of the invention relates 20 to the configuration of the work engaging ends of the nail tubes whereby the nails are somewhat counter-sunk when driven.

For a more complete understanding of 25 this invention together with further objects and advantageous details and combinations of parts, reference may be had to the accompanying drawings illustrating an embodiment thereof in which,

30 Fig. 1, is a partial side elevation of a heel nailing machine employing this invention showing a shoe partly broken away in position therein.

Fig. 2, is a side elevation of the shoe supporting jack assembled on the machine, 35 other parts of which are shown in section.

Fig. 3, is a similar view with the jack shown partly in vertical section.

Fig. 4, is a sectional detail of a nail-driver carrying block taken substantially on the 40 axis of the driver-securing set-screw.

Fig. 5, is a horizontal section on line 5—5 of Fig. 2, and,

Fig. 6, is a plan of the jack head.

At A in Fig. 1, is shown a machine pedestal having journaled from front to rear therein adjacent its base, an actuating shaft 1 having a driving pulley 2 at the rear of the machine. Fixed at the forward end of this shaft is a crank 3 having a connecting rod 4 pivoted thereto and to the lower end of a plunger 5 vertically slidable in a guideway 6. At 7 is shown a forwardly projecting table having a slideway formed in its upper surface for the reception of a shoe

supporting jack 8. Held by a vertically 55 movable bracket 9 projecting forwardly from the upper portion of the base A, is a heel engaging clamp indicated generally by 10 and which is shown as having a top-lift engaging member 11, and a forked member 60 12 engaging opposite sides of the heel between its ends. At 13 is shown a nail loading block having a series of tubes 14 communicating therewith and through which 65 nails may be fed into the block, heads downwardly. The jack 8 may be positioned beneath the heel clamp as shown in Fig. 1, or it may be moved in the slideway into co-operative relation with the loading block 13 from which nails may be fed into the nail 70 tubes in the jack as presently described.

Referring more particularly to Figs. 2 and 3, jack 8 is provided with a handle 15 having pivoted thereon a lever 16 with an upwardly directed finger piece 17 normally 75 held outwardly from the handle by means of a spring 18. The outer end of the lever 16 is slotted and takes over a transverse pin 19 fixed in a latch bolt 20 slidable vertically in the base of the jack and engagable in a 80 perforated latch plate 21 fixed at the outer end of the table 7. This latch mechanism serves to retain the jack in proper position relative to the heel clamp during the nail driving operation. The upper end of the 85 jack carries a head 22 having a plurality of slots or slotted openings as shown at 23 and 24. A series of detachable plates 25 having circular openings 26 variously spaced along the slots or slotted openings may be interchangeably fixed on the upper face of the head 22 by means of screws 27 and 28. Seated within the openings 26 are the upper 90 ends 29 of nail tubes 30, each nail tube being fixed at 31 by a threaded engagement therewith in the upper end of a driver guide member 32. Below the portion 31 each guide 32 is formed with side bars 33 and 34, as shown in Fig. 4, between which is slidably guided a block 35 having flanges 36 and 37 engaging one edge of each of the bars 33 and 34, and a plate 38 over-lapping the opposite edges of the bars 33 and 34 is made fast to the block 35 by screws 39 and 40. Block 35 has a threaded perforation at 41 95 for the reception of the lower threaded end of a nail driver 42 which projects within the nail tube 30 and is reciprocable therein.

2
by reciprocation of the block 35. A set screw 43 acting against a brass block 43' retains the driver 42 in adjusted position. The lower ends of the side bars 33 and 34 merge in a solid extension 44 having formed at its lower end a series of rack teeth 45 engageable with a worm 46 of high pitch carried by an adjusting screw 47, the inner end of which is threaded with a very low pitch 10 in a perforation 48 in the body of the jack. Each screw 47 has a knurled head 49 by which it may be turned. In order to properly guide the lower ends of the driver guides as adjusted by means of screws 47, 15 jack 8 is provided with a series of pairs of outstanding fins 50 and 51 between which the portions 44 may slide, a guide screw 52 passing through each fin 51 projecting into a guide slot 53 in one face of each member 20 44.

As shown in Fig. 3, jack 8 has a central vertical perforation 54 merging at its lower end in an enlarged recess 55. Slidably carried within the perforation 54 is a nail driver actuating rod 56 having a head 57 on its lower end slidable within the recess 55. When the jack is in nail driving position the head 57 is in alignment with the plunger 5 so that on actuation of the latter the 30 head 57 is impinged thereby and the rod 56 driven upwardly. Head 57 is screwed to the lower end of the rod 56 so that the relative positions of the parts may be adjusted to determine the length of stroke of the rod 56. 35 The upper end of this rod is reduced in diameter at 58 for the reception of a collar 59 which is retained in position by means of a nut 60 threaded on a still further reduced extremity 61 of the rod 56. As shown more 40 particularly in Fig. 5, collar 59 has a series of pairs of outwardly extending ears 62 corresponding in number to the number of nail tubes and nail drivers, a link 63 being pivoted at one end between each pair of ears 45 and at its other end between a similar pair of ears on each of the blocks 35. By this means vertical reciprocation of the rod 56 will impart reciprocation to the blocks 35 and consequently impart driving and re-50 tracting strokes to the nail drivers 42 simultaneously, regardless of the spacing of the nail tubes or their angular relationship.

In order to provide a suitable pivotal connection for the upper ends of the nail tubes 55 within the plate 25, and also to provide means whereby the nails as driven may be counter-sunk somewhat in the work, the ends of the nail tubes at 29 are formed substantially spherical each having a central perforation as shown at 64 (Fig. 6) forming the upper end of the nail receiving opening. The upper ends of the slots and openings 23 and 24 are widened to form bearings 60 against which these spherical heads are supported, to retain their upper ends projected 65

above the upper surface of plate 25. At diametrically opposite sides of the perforations 64 and closely adjacent thereto, these substantially spherical ends are recessed as shown at 65 and 66, this construction producing 70 a tapered end having curved work indenting spurs at 67 and 68 on opposite sides of the nail opening which under the pressure exerted by the heel clamp penetrate the surface of the work so that the end 75 of the nail tube indents the surface thereof at the point where the heads of the nails will be driven at the end of the driving stroke. This construction causes the nails when driven to be slightly counter-sunk so 80 that there is no danger of the nail heads projecting above the surface of the sole and annoying the wearer of the shoe. The recesses 65 and 66 form convenient tool engaging portions by which the nail tube may be 85 turned within the threaded end of the guide 32 for adjustment or removal.

In the operation of this machine, the jack, with no shoe thereon, is unlatched and pushed rearwardly into cooperative relation 90 with the nail loading block 13 whereupon a nail is fed head downwardly into each of the nail tubes, the head resting on the upper end of the corresponding nail driver. The jack is then moved forwardly and a shoe is placed 95 thereon substantially as shown in Fig. 1, the heel clamp being brought downwardly to hold the heel in proper position and to press the shoe downwardly to cause the ends of the nail tubes to indent the sole surface as above described. On actuation of the crank 3, the plunger 5 is then caused to impinge on the head 57, raising the rod 56 and, through its connections with the nail drivers 100 imparting the driving stroke thereto. Further motion of the crank 3 retracts the plunger 5 and in its fully retracted position the machine stops. This allows the rod 56 and the drivers to descend by gravity, and retracts the plunger 5 sufficiently to allow the 105 jack to be moved in its slideway into nail loading position for a subsequent operation. On raising the bracket 9 to release the heel clamping members the nailed shoe may be 110 removed.

In order to position the nails for various sizes of shoes a plurality of plates 25 are provided having openings for the spherical ends of the nail tubes differently spaced 115 therein, these spherical ends of the nail tubes being readily centered in the openings in the nail plate as it is placed in position. In order to adjust the direction in which the nails shall be driven, the angular relation of the nail tubes may be varied within the 120 necessary limits by turning the adjusting screws 47. These various adjustments can be made without affecting the connections of the drivers to the actuating mechanism. This construction makes possible the use of 125 130

the same nailing jack for a great variety of sizes and styles of shoes and eliminates the necessity, often arising when using non-adjustable nail driving blocks, of omitting one or more of the nails which would otherwise be driven in such relationship to the heel as to cause danger of splitting, or of using nails of various lengths in the different nail tubes.

Having thus described an embodiment of this invention, it should be evident to those skilled in the art that many changes and modifications might be made therein without departing from its spirit or scope as defined by the appended claims.

15 I claim—

1. In a heel-nailing machine, a shoe-supporting jack, a plurality of nail driving mechanisms disposed within said jack, means for simultaneously actuating said mechanisms, and means for angularly adjusting each of said mechanisms with respect to the others to vary the spacing of the nails.

2. In a heel-nailing machine, a shoe-supporting jack, a plurality of nail driving mechanisms disposed within said jack, means for simultaneously actuating said mechanisms, and manually operated adjusting means for determining the relative directions of said mechanisms and thereby the directions in which the nails are driven.

3. In a heel-nailing machine, a shoe-supporting jack, a nail tube disposed in fixed position within said jack, and manually operated means for angularly adjusting said tube from one fixed position to another to determine the driving direction of the nail.

4. In a heel-nailing machine, a shoe-supporting jack, a plurality of nail drivers secured in fixed positions within said jack, and means for angularly adjusting the fixed

positions of each of said drivers independently of the others to determine the driving angle thereof.

5. In a nailing machine, a plurality of nail tubes having substantially spherical ends, a plate having bearing openings engageable with said ends for spacing the same, and means for independently adjusting the angular relationship of said tubes to said plate.

6. In a nailing machine, a plurality of nail tubes having substantially spherical work-engaging ends, a plate having bearing openings engageable with said ends for spacing the same, means for adjusting the relative spacing of the work-engaging ends of said tubes, a nail driver reciprocable in each nail tube, and means for simultaneously actuating said drivers.

7. In a nailing machine, a plurality of nail tubes, a plate having openings in each of which the delivery end of a nail tube is pivoted, and means for swinging each of said tubes about its pivot independently of the others.

8. In a nailing machine, a nail tube pivoted adjacent one end, a driver reciprocable in said tube, a driver guide fixed to the free end of said tube and carrying rack teeth, and a worm engaging said rack teeth and by the turning of which said nail tube may be swung on its pivot.

9. In a nailing machine, a work-supporting jack, a nail-tube having a substantially spherical work-engaging end, and a bearing seat provided by said jack affording a pivotal support for the delivery end of said nail-tube.

In testimony whereof, I have signed my name to this specification.

FRED A. REARDON.
